UNITED STATES PATENT OFFICE.

SAMUEL W. BUERCKLIN, OF PRAGUE, OKLAHOMA.

STRINGED MUSICAL INSTRUMENT.

No. 921,507.

Specification of Letters Patent.

Patented May 11, 1909.

Application filed December 14, 1903. Serial No. 467,439.

To all whom it may concern:

Be it known that I, SAMUEL W. BUERCKLIN, a citizen of the United States, and a resident of Prague, in the county of Lincoln and

5 State of Oklahoma, have made certain new and useful Improvements in Stringed Musical Instruments, of which the following is a specification.

My invention is an improvement in 10 stringed musical instruments, and consists in certain novel constructions and combinations of parts hereinafter described and claimed.

Referring to the drawings forming a part 15 hereof—Figure 1 is a plan view of the improvement. Fig. 2 is a side view. Fig. 3 is a section on the line 3—3 of Fig. 1.

The present embodiment of the invention comprises a neck 1, with a tail piece 2, and 20 a bridge 3, all of which are supported upon a resonant body to be presently described. The neck is provided with the usual head 4, and strings 5 extend from the head to the tail piece, passing over the bridge.

25 The resonant body, before mentioned, is substantially circular in cross section, and gradually increases in size from one end to the other, the larger end being provided with a bell 6, while the smaller end is provided 30 with a sound box 7, upon which is mounted the bridge. The resonant body extends from the sound box outwardly thence rearwardly substantially parallel to the tail piece, then transversely, and substantially parallel 35 with the tail piece to a point beyond the bridge, where the said body crosses below the strings and the finger board and is then bent upwardly and gradually merged into the bell which is arranged above the finger 40 board as clearly shown in Fig. 1. The tail piece is connected with a button 7^a, on the transverse portion of the resonant body, and chin rest 8 may be connected with the body in proper position to receive the chin of the 45 performer. The finger board is supported by the neck, which is connected to the resonant body by braces 9, 10, and 11.

The bridge 3, is mounted on a spring plate 50 13, which plate is arranged transversely of the bridge as shown in Fig. 2, the bridge being slotted for receiving the spring and the ends of the spring are received in slots in the arms 14 of a bracket 15, which bracket is

shaped to fit the periphery of the sound box, and may be secured thereto by screws 16. 55 The bridge is secured to the spring by soldering or in any other suitable manner.

A side of the sound box is engaged by the angular portion 18 of a lever 19, which is pivoted to an arm 20, integral with the bridge 60 and extending from one corner thereof. A set screw 21 is threaded through the upper end of the lever 19, and rotatably connected with the arm 20.

The object of the above construction is to 65 adjust the force with which the arm engages the sound box, and to compensate for wear between the end of the arm and the box.

While I have shown and described the improvement embodied in an instrument of 70 the violin type, it is evident that it might be embodied with equal facility in instruments of the guitar or mandolin type.

I claim:

1. In a device of the class described a 75 hollow resonant body gradually increasing in cross section from one end to the other, the smaller end being provided with a sound box, a bridge supported by the sound box and having an arm extending therefrom 80 alongside a side of the sound box, a lever hinged to the arm and having an angular portion engaging the sound box side, means for adjusting the position of the lever with respect to the sound box, a tail piece supported 85 by the body, a neck supported by the body on the opposite side of the body from the tail piece, and strings connecting the tail piece and neck and resting upon the bridge.

2. A device of the class described comprising a hollow resonant body gradually increasing in cross section from one end to the other, a sound box at the smaller end of the resonant body, a bridge supported by the sound box and provided with an extending 95 portion engaging a side of the sound box, means for adjusting the extended portion with respect to the sound box, a tail piece and a neck supported by the body on opposite sides of the bridge and strings connecting 100 the neck and the tail piece and resting upon the bridge.

SAMUEL W. BUERCKLIN.
